UNITED STATES PATENT OFFICE.

RALPH H. UPSON, OF AKRON, OHIO, ASSIGNOR TO THE GOODYEAR TIRE & RUBBER COMPANY, OF AKRON, OHIO, A CORPORATION OF OHIO.

DIRIGIBLE AND THE LIKE.

Application filed July 20, 1918. Serial No. 245,940.

To all whom it may concern:

Be it known that I, RALPH H. UPSON, a citizen of the United States, residing at Akron, in the county of Summit and State of Ohio, have invented new and useful Improvements in Dirigibles and the like, of which the following is a specification.

The present invention relates to improvements in balloons of the dirigible type and the like and more particularly to improvements in nose caps or, cups for preventing the caving in or cupping of the nose of the balloon.

In the drawings, wherein there has been illustrated a preferred embodiment of the invention as it is reduced to practice, and throughout the several views of which, similar reference numbers designate corresponding parts:

20 Fig. 1 is an end elevation of the nose portion of the balloon;

Fig. 2 is a vertical section of the nose;

Fig. 3 is a diagrammatic view of the nose before the elements of this invention are 25 completely assembled thereon; and

Fig. 4 is a similar view after the application of metal nose cup.

The difficulties experienced in designing battens of the old type were many, as for 30 instance, in providing battens that were flexible enough to allow for or compensate for the various pressures experienced and at the same time provide an article of sufficient stiffness to withstand the excessive 35 pressures, to which they are subjected. One expedient has been to increase the number of battens and also increase their size and thickness, which greatly increased the weight and hampered the design of the nose. 40 Another difficulty was in preventing the breaking of the light battens which invariably resulted in a complete cave in of the nose.

Accordingly in the present invention the 45 nose of the balloon envelope is formed with a slightly sharpened rounded point reinforced by placing a metal plate or nose piece in front of the envelope. The battens used are of very light construction and are 50 incorporated into the envelope in the usual manner but instead of terminating at a common point, they are arranged at spaced intervals so that the ends lie in a circle of a slighter diameter than the largest diameter 55 of the reinforced metal nose.

In the drawings, the numeral 10 represents the envelope proper, 11 the metal nose piece cup and 12 a series of battens. The metal nose is so designed as to afford an air space between the envelope proper and the nose to permit of the clamping of the ends of the battens between the annular clamping rings 13 and 14 interposed between the metal nose 11 and the envelope 10. Suitable machine screws or other fastening means 15 may be employed to securely bind the metal nose and the outer clamping ring together. The clamping rings 13 and 14 are clamped together by a series of clamping bolts 16 which are inserted through the rings at the 20 intervals between the battens which does away with the necessity of boring holes through the battens and thereby weakening them.

Preferably, the clamping rings 13 and 14 are constructed with cooperating inner faces that occupy, when the rings are clamped to the nose cup, a position of greater angularity, with respect to the horizontal, than that normally assumed by the 25 battens 12, when the envelope is inflated, and before the rings and nose cup are positioned relative thereto. Hence, when the rings and nose cup are fully clamped in position each batten is tilted or adjusted about a fulcrum point intermediate the contiguous faces of the rings and the rear portion of each batten behind the rings, and is moved to a position of slightly greater inclination to the major axis of the envelope, whereas, a reversed motion of lesser degree is imparted to the forward end of each batten. This action 30 results in tensioning the nose portion of the balloon fabric behind the rings, or that portion thereof that is not covered by the cup 35 proper 11.

Fig. 3 of the drawings illustrates diagrammatically the position of the nose of the envelope before attaching the metal nose-piece and securing thereto the rings 13 and 14 and also the angle formed by a line drawn tangential to the bag with the horizontal, and Fig. 4 illustrates how the angle, which the tangential line makes with the horizontal, is increased from—say 58 to 60 40 degrees by clamping together the metal nose piece and the application of the clamping rings 13 and 14. This change of angle 45 causes the battens to pull the fabric taut on the nose of the envelope as above described, 50

thereby decreasing the tendency to cup or cave in under excessive pressures.

It is to be understood that the invention is not limited to the particular angles, 58 and 60 degrees, as these angles may be changed and others used in different designs of air craft.

What I claim is:

1. The combination with the envelope of 10 an air craft having a nose portion, of a relatively rigid nose cup mounted in front of the nose portion of the envelope, and devices cooperating with the edge of the cup adapted to secure the cup upon the envelope in spaced 15 relation with respect thereto.

2. The combination with the envelope in 20 an air craft of the character described of a nose member of relatively rigid shape mounted in front of the nose portion of the envelope; a plurality of battens secured to the envelope and radiating rearwardly from the nose cup; and clamping members for 25 securing the peripheral edge of the nose cup to said nose portion and connecting the forward ends of the battens to the nose cup.

3. The combination with an air craft of the character described of a sheet metal nose cup mounted in front of the nose portion of the envelope in spaced relation with respect 30 thereto a plurality of battens having their forward ends detachably secured to the nose cup; and means securing the battens to the envelope.

4. The combination with the envelope of 35 an air craft of the character described of a cup shaped metal nose piece adapted to fit over and in front of the nose portion of the envelope, a plurality of battens radiating rearwardly from the nose cup and attached 40 to the envelope, and a pair of clamping rings secured interiorly of the nose cup and receiving between them the forward ends of the battens whereby the battens are rigidly 45 and detachably connected to the nose cup.

5. The combination with the envelope of 50 an air craft having a nose portion, of a plurality of battens affixed to the nose portion, a relatively rigid nose cup adapted to guard 55 said nose portion, and means for securing the nose cup to the envelope adapted upon application to adjust the battens to thereby tension a portion of the nose of the envelope.

6. The combination with the envelope of 55 an air craft having a nose portion, of a plurality of battens affixed to the nose portion, a relatively rigid nose cup mounted in front of said nose portion of the envelope and having a greater degree of concavity than 60 the nose portion, and means for securing the nose cup to the envelope adapted upon application to adjust the battens to tension a portion of the fabric of the envelope.

7. The combination with the envelope of 65 an air craft having a curved nose portion,

of a dome shaped nose guard of greater curvature than said nose portion, and annular elements for securing the peripheral edge of the guard to the nose portion and spacing said guard therefrom to provide an 70 air chamber therebetween.

8. The combination with the envelope of 75 an air craft having a curved nose portion, of a dome shaped nose guard of greater curvature than said nose portion, and annular opposed elements for securing the peripheral edge of the guard to the nose portion and spacing said guard therefrom to provide an air chamber therebetween.

9. The combination with the envelope of 80 an air craft having a curved nose portion, of a dome shaped nose guard of greater curvature than said nose portion, a plurality of battens secured to the envelope and radiating rearwardly from said guard, and opposed clamping elements for securing the peripheral edge of the guard to the nose portion and spacing said guard therefrom to provide an air chamber therebetween.

10. The combination with the envelope of 90 an air craft having a curved nose portion, of a dome shaped nose guard, a plurality of battens radiating rearwardly from said nose guard, means engaging the edge of the guard for securing said guard upon the nose portion in spaced relation with respect thereto, and means coacting with said first means to hold the battens in relatively fixed relation.

11. The combination with the envelope of 100 an air craft having a curved nose portion, of a dome shaped nose guard of greater curvature than said nose portion, a plurality of battens radiating rearwardly from said nose guard, means engaging the peripheral edge of the guard for securing said guard upon the nose portion in spaced relation with respect thereto, and means coacting with 105 said first means to hold the battens in relatively fixed relation.

12. The combination with a balloon envelope comprising a nose portion, of a plurality of battens incorporated in the material of the nose portion, a guard adapted to be mounted upon the battens in enclosing relation to said nose portion, and means for mounting the guard upon the battens adapted upon application to adjust the battens to tension an adjacent portion of the envelope.

13. The combination with a balloon envelope comprising a nose portion, of a plurality of battens incorporated in the material of the nose portion in co-incidence with the major axis of the envelope, a nose guard adapted to be mounted upon the forward end of the battens in enclosing relation with respect thereto and to a portion of said material, and means for mounting the guard upon the battens adapted upon application to adjust the rear ends of the battens away from 130

the axis of the envelope to tension the un-
enclosed material of the nose portion.

14. The combination with a balloon envelope comprising a nose portion, of a plurality
5 of battens incorporated in the material of
the nose portion of the envelope in co-in-
cidence with the major axis of the envelope,
a rigid substantially conical nose cup adapt-
ed to cover the forward surface of the nose
10 portion, and means for mounting the cup
upon the forward end of the battens com-
prising telescopic rings adapted for appli-
cation to clamp the forward ends of the

battens therebetween and provided with co-
operating faces for engaging the battens ar-
ranged at an angle to the horizontal whereby
when said rings and cup are applied the bat-
tens are adjusted to tension the unenclosed
material of the nose portion. 15

In testimony whereof, I have signed my 20
name in the presence of two subscribing
witnesses.
